UNITED STATES PATENT OFFICE.

MORRIS CRAMER, OF CLEVELAND, OHIO.

HANDLE FOR CUTTING-TOOLS, DIE-STOCKS, &c.

1,215,119.

Specification of Letters Patent.

Patented Feb. 6, 1917.

Application filed July 22, 1916. Serial No. 110,638.

To all whom it may concern:

Be it known that I, MORRIS CRAMER, a citizen of the United States, residing at Cleveland, in the county of Cuyahoga and State of Ohio, have invented a certain new and useful Improvement in Handles for Cutting-Tools, Die-Stocks, &c., of which the following is a full, clear, and exact description, reference being had to the accompanying drawings.

The general object of this invention is to so arrange a handle for cutting tools, such as die stocks, pipe cutters, and the like, that it may serve as a reservoir for oil to be led to the surfaces operated on. More specific objects are to so construct such a handle that it may be simple, efficient, cheaply manufactured, and have means for conveniently releasing the desired amount of oil in connection with means for leading it to surfaces on which work is being performed. A feature of my invention is the provision, in a handle of convenient shape and size, of such means for conducting oil to the desired point.

My invention is hereinafter more specifically described in connection with the accompanying drawings, and the essential characteristics are set forth in the claims.

30 In the drawings, Figure 1 is a side elevation of a multiple die stock showing my reservoir handle in position; Fig. 2 is a longitudinal axial section through such handle; Fig. 3 is a side elevation of the same showing the means for releasing the oil in an open position; Fig. 4 is a transverse central section through the die stock showing a pipe being threaded and showing the oil tube leading from the handle to the threaded portion thereof.

Handles constructed according to my invention may be used on die stocks having one or a plurality of sets of dies or on pipe cutting tools, or any like tools where it is 45 desirable to lubricate the tool and the surface operated upon while in operation. The embodiment shown in the drawings is illustrative of any of such uses.

Referring to the drawings by numerals, 50 the die stock shown is a box-like structure comprising a hollow frame made in two parts 5 and 6 preferably duplicates of each other and secured together by pintles 8 extending through registering openings in laterally projecting ears 9, thus removably securing these parts together. 10 indicates

the cutting die suitably secured in position inside these members to which access is had by separating the frame parts 5 and 6 and to which pipes to be threaded may be 60 guided by bushings such as indicated at 11 in outwardly extending sleeves 12 serving as guides for these bushings and rigidly carried by the frame parts. At the ends of the frame are provided arms 15 and 16 65 rigid with the frame parts 5 and 6 respectively, and so arranged as to overlap and receive the threaded ends of handles. Ordinarily substantially cylindrical members such as indicated at 18 (at the right of 70 Fig. 1) are used and are provided with a threaded portion 19 engaging the registering threaded openings in the arms 15 and 16. As stated, this die stock may be of any 75 suitable structure. For a more complete description of the particular one shown, reference may be had to the application of John B. Martens, die stocks, Serial No. 95,462, filed May 4, 1916.

The construction of the handle with which 80 this invention is concerned is as follows: The body or shank 25 of the handle comprises a hollow cylindrical tubular member shown as suitably threaded at 26 for engagement with the die stock frame, and closed 85 at its upper end by a cap member 30 having interior threads 31 co-operating with threads on the exterior of the outer end of the handle. The cap is shown as provided with flattened side portions 32 for engagement 90 with a wrench or other suitable tool by which it may be tightly screwed in position. The outer end of the cap is provided with a concave depression 35 extending inwardly to an axial hole which serves as a guide for 95 a plunger 36 rigid with an outwardly extending flange 37, and between this flange and a shoulder on the inner side of the cap is a rubber or fibrous washer 38 acting to close vent openings 39 leading through the 100 cap adjacent to the plunger 36. The outer end of the plunger normally stands beneath the outer end of the cap so that the plunger may be protected by the cap from inadvertent depression.

Screwing into the plunger 36 is an axially positioned rod 40 having on its lower end a valve head 42 provided with a beveled surface adapted to co-operate with a corresponding valve seat in a plug 45 rigidly secured in the lower end of the tube member 110 25. A passage 46 is shown as surrounding

the rod 40 and leading to the valve seat which flares toward a chamber 47 containing a spring 48 adapted to urge the valve 42 to this seat and at the same time move 5 the plunger upwardly seating the washer 38 to tightly close the vent openings 39. The spring 48 bears at its lower end in a portion of a plug 50, the plug 50 having a threaded portion 51 engaging internal 10 threads on the plug 45 and carrying a tube 52 communicating with the chamber 47 below the valve and adapted to lead the oil to the surface where it is required.

The tube 25 forms a reservoir which may 15 be filled with oil by removing a small threaded plug 54 in the side of the tube and inserting the oil through the opening closed thereby. A handle may then be placed in position on the tool with which it is to be used and when used with a die stock, such as shown in the drawings, the tube 52 is turned so that it may extend to a point adjacent the dies to be used, as illustrated, for example, in Fig. 1 where the tube leads to 20 threads on a pipe 60 which is being operated upon by the die stock. Here the end of this tube extends to the adjacent side of the pipe at a point where the threads are being cut, and it will be seen that when the 25 pipe is in a vertical position, oil, released by depressing the plunger 36 opening the valve 42, will flow through the tube 52 to the point where it is to be used coming on the surfaces where the threads are being cut and 30 facilitating the cutting operation.

In order to bring the tube 52 to the set 35 of dies being used, it is necessary to rotate the handle 25. It is desirable to prevent rotation of the handle after the tube 52 is 40 positioned by means of a latch carried by the handle. This latch is shown as comprising a pivoted member 65 having nose portion 66 adapted to engage notches 67 in the frame, and urged into any of these 45 notches by a spring indicated at 68. The latch member 65 is shown as pivoted by a suitable bracket 69 to the side of the handle. The position of this latch is preferably on the same side of the handle 25 as that toward 50 which the tube 52 leads so that it may serve to indicate the position of this tube, there being as many notches 67 as there are sets of dies, and spaced relative to these dies. It is apparent from Fig. 4 that it would 55 be only necessary to swing the tube 52 around within the frame to direct oil to any of the sets of dies.

Heretofore it has been common practice 60 with such tools to stop the cutting operation at intervals while the operator lubricated the cutting tool and surfaces by means of an oil can. This usually results in a waste of oil as more oil is put on at any one time than necessary, whereas, with my device, the 65 oil may be brought to the cutting tool as

often as desired, being only necessary for the operator to depress the plunger with his thumb while the handle is in a position to cause the oil to run toward the cutter. Thus a small amount of oil used at frequent intervals prevents waste, saves time, and secures more efficient lubrication.

Having thus described my invention, what I claim is:

1. The combination with a die stock having a number of separate cutting dies, a handle secured to the stock for rotating the same and comprising a hollow tubular member adapted to carry oil, a tube leading from the inner end of the handle and movable so that it may be brought to a position to lead oil to any one of the dies.

2. The combination with a die stock having a number of separate cutting dies, a handle secured to the stock for rotating the same and comprising a hollow tubular member adapted to carry oil, a tube leading from the inner end of the handle and bent laterally therefrom and movable so that it may be brought to a position to lead oil to any one of the dies, and a manually operated valve controlling said passage for intermittently discharging oil to the surfaces operated on.

3. The combination with a multiple die stock wherein dies are arranged substantially in the same radial plane, a handle secured to said stock at substantially right angles to said plane, said handle comprising a tubular member, a plug closing the outer end of said tubular member having a vent opening, a valve closing said opening, a passage including a tube leading from the inner end of the handle to the interior of the die stock, said tube being bent and revoluble and adapted to be rotated whereby it may be positioned to lead oil to any of the dies, a valve controlling said passage and connected with the first mentioned valve, and means for manually operating both valves.

4. The combination with a die stock having a number of separate cutting dies, a handle secured to the stock for rotating the same and comprising a hollow tubular member adapted to carry oil, a tube leading from the inner end of the handle, said handle rotatably engaging the die stock to bring said tube to a position to lead oil to any one of the dies, and a latch adapted to secure the handle in any one of said positions.

5. The combination with a hand operated cutting tool, of a handle therefor comprising a tube, a cap closing one end of the tube and having a vent opening leading longitudinally toward the tube, a plunger extending through the cap, a rod axially positioned in the tube and connected with said plunger, said plunger having a laterally extending disk closing the vent opening, a

plug closing the inner end of the tube, a valve seating in said plug, a spring pressing against said valve from the inner end of the handle, a receptacle around said valve formed in said plug, and a compression spring in said receptacle to close the valve and the vent opening, and a passage for leading oil from the inner end of the tube.

6. The combination of a die stock having a number of separate cutting dies radially arranged, a handle secured to the stock for rotating the same comprising a tubular member adapted to carry oil and positioned substantially at right angles to the axis of the dies, a tube extending from the inner end of the handle and bent so that it may be brought to position to lubricate any of said dies by rotating the handle, a latch adapted to engage the die stock and the handle with means operated by the finger to release such engagement.

7. The combination of a die stock having a number of separate cutting dies radially arranged, a handle secured to the stock for rotating the same comprising a tubular member adapted to carry oil and positioned substantially at right angles to the axis of the dies, a tube extending from the

inner end of the handle and bent so that it may be brought to position to lubricate any of said dies by rotating the handle, a latch pivoted to the handle and indicating the direction of the tube inside the stock and adapted to engage the stock adjacent the handle to hold the handle in any position given it.

8. The combination with a die stock member having a number of separate cutting dies radially arranged on the inner side thereof, a handle member secured to the stock and rotatably engaging the same and comprising a hollow tubular member adapted to carry oil, a single bent tube leading from the inner end of said handle member and adapted to have its inner end brought to a position adjacent any of said dies by rotating the handle, a latch secured to one of said members, the other of said members having notches adapted to be engaged thereby, and yielding means adapted to hold the latch in said engagement and be released by a finger of the operator.

In testimony whereof, I hereunto affix my signature.

MORRIS CRAMER.
